EMILIO SILVANO AND VINCENZO LOMBARDI CERRI, OF GENOA, ITALY

DEVICE FOR WASHING MATERIAL

Application filed December 6, 1927, Serial No. 238,811, and in Italy December 14, 1926.

The present invention relates to a novel process for washing material previously pulverized and rendered granular or soft with solvent, and it relates also to the device by which the process is carried out.

The invention finds a convenient and direct use in washing seeds and oily cakes with solvent, for the purpose of extracting the oil. It may also be successfully applied when any raw material, susceptible of being previously pulverized and rendered soft or granular, is to be washed with a liquid, without being carried away by this washing liquid.

The invention has been realized in practice and is characterized by the following features:

The material to be washed, after being previously and suitably prepared, is submitted to the washing in rather thin layers of suitable breadth;

The washing is effected by causing the liquid and solvent to pass through the layer in a normal direction.

In order to permit this operation, the layer to be washed is placed between two continuous transporting and retaining ribbons consisting of flexible material, which, will prevent the smallest particles from being washed away and is also suitable to act as a filtering means, permitting the washing liquid to pass through it.

The assembly consisting of the two continuous retaining and transporting ribbons and of the material contained between them, is such that the layer of material to be washed cannot move between the ribbons nor go out therefrom when the washing liquid passes through it.

During the passage of the liquid through the ribbons containing the material to be washed, the smallest particles of material close the holes of the ribbon which acts as a filtering means, thus impeding a second passage of liquid in the same direction, should no other measures be taken. In order to obtain a succession of passages of washing liquid through the assembly, the device is so arranged that the said assembly is traversed by the washing liquid or solvent, first in one direction and then in the opposite direction,

but always in a direction essentially perpendicular to the layer of the material, with the result that each passage of liquid frees the closed holes of that ribbon which in the preceding passage had acted as a filtering means. 55 Owing to the aforementioned advantage, it is possible to submit the same material to several successive washings, as well as to invert the assembly containing the material in respect to the washing liquid. 60

The washing operation is effected causing the assembly which consists as mentioned above, of the two ribbons and of the material contained between them, to become adjacent to a surface which is perforated and suitable either for directing the washing liquid against the assembly to be washed, or to receive the liquid passed through said assembly and which may be further used in successive washing operations. 70

Said assembly after having been traversed an even number of times by the washing liquid in each direction, and after this liquid has washed the material contained between the two ribbons, is separated for the purpose 75 of withdrawing and removing therefrom the washed material as well as for filling it again in a suitable way with other material to be washed;

The filling of the assembly with other material to be treated is carried out in such a way that the material completely fills up the space between the transporting and retaining ribbons so that the material is prevented from moving between the ribbons in longitudinal direction under the action of the washing liquid; 85

When, for industrial purposes, it is necessary to recover the washed material or the washing liquid absorbed or carried by said material after the treatment, proper means will be applied to the assembly, and it will be also possible to apply means suitable for drying the washed material either before or after removing it from the transporting and retaining ribbons; 95

Finally, should the washing liquid evaporate easily at ordinary temperatures and at atmospheric pressures or deteriorate under the action of light or under other adverse atmos- 100

pheric conditions, then the device is placed in a closed container where it will be possible to maintain suitable temperature and pressure or to eliminate the action of the light or of 5 said other adverse atmospheric conditions which cause any inconvenience.

The accompanying drawings illustrate only by way of example, a practical embodiment of the invention based on the afore- 10 said principles and relate particularly to the treatment of seed and cakes, consisting in washing them with solvent for the purpose of extracting the oil contained therein, although the invention is suitable for many 15 other operations.

The washing of the material may be effected either by causing the assembly composed of the transporting and filtering ribbons, (containing the material to be washed) to 20 move adjacent to a surface—preferably cylindrical and rotating so that the peripheral speed of said surface is equal to the displacement of the aforementioned assembly, or by providing an apparatus having a double ribbon 25 which remains flat and passes, at the portion submitted to the washing, between two flat, fixed and perforated plates, having corresponding holes. One of said plates is a wall of a first open tank, the other a wall of a sec- 30 ond closed tank or chamber whose volume may be caused to vary.

The washing liquid contained in said second chamber, owing to continuous variations of volume, is forced under pressure through 35 the aforesaid double retaining layer, and also through the material contained therein; the washing liquid may be conveyed either into the upper tank or to the lower chamber, in both cases it enters into the tank or chamber 40 at the point where the double ribbon moves out of the device and leaves it at the point where the double ribbon containing the material to be washed is introduced into the device.

45 The same means which produces the aforesaid variations of volume and the successive passages of the liquid through the material to be washed, serves also to give to such liquid a movement which forces it through a 50 discharge valve to effect a renewal of the washing liquid since during the passage through the device the washing liquid is enriched with the material dissolved therein and which was contained in the raw mate- 55 rial carried between the two aforesaid continuous ribbons.

Figure 1 illustrates schematically the complete device and its operation; Fig. 2 is a cross section of the transporting and retain- 60 ing ribbons; Fig. 3 is also a cross section of the two ribbons and Fig. 4 shows in part an axial section and in part an outside view of the two drums employed in the scheme of Fig. 1.

65 Figs. 5 and 6 show schematically in verti-

cal section two devices which may replace the device shown in Fig. 4 and which are modifications of Fig. 1.

Referring more particularly to the drawings, transporting ribbon (1) and retaining ribbon (2) are shown in separated position at (A) and (B) in Fig. 1. The ribbon (1) is guided by a recoil roller (18) to assume a horizontal or substantially horizontal position and is disposed to pass below a funnel (19) or similar device of a hopper (20), said funnel (19) distributing a uniform and continuous stratum on the upper surface of said ribbon. The thickness of said stratum must slightly surpass the height (h), Fig. 3, of the space resulting between the transporting and retaining ribbons, after they are coupled. The breadth of such stratum deposited by the funnel (19) on the ribbon (1) must be slightly less than the breadth "b", Fig. 3, of the space resulting between the two ribbons when they are coupled. In such a way the raw material to be treated becomes suitably pressed by the two ribbons and therefore is compelled to move with them as long as they are coupled and said raw material is prevented from shifting in a longitudinal direction and from getting out of the space formed by the coupling of the ribbons, under the action of the passage of the washing liquid or solvent 95 through it.

Their two ribbons (1) and (2) after the passage under the recoil roller (21) make contact, and after the passage of both of them on the roller (4) they form by means of said retaining means (26) an assembly containing the stratum of the raw material to be washed which is retained in a suitable and reliable way; said assembly so constructed forms a characteristic of the present invention.

The assembly so constituted (Fig. 3) is moved in the direction of the arrow (25) by means of trailing rollers and becomes adjacent to a portion of the washing cylinder barrel (7), Figs. 1 and 4, provided with the holes (22). Said cylinder, which is empty, rotates around its axis; its speed of revolution is such that the linear speed of its outer surface is equal to the speed of displacement of the ribbons in the direction of the arrows (25). The height of the cylinder (7) corresponds to the breadth of the assembly composed of the two ribbons (1) and (2), and the holes (22) are uniformly distributed on a portion as wide as that of the band of the material to be treated; this band, by means of suitable side guide rollers or the like, lies flat on the perforated outer surface of the cylinder. The washing liquid is supplied through the centre hole (8) (with reference to the case illustrated) and reaches the interior of the concave cylinder. It then passes through the holes (22) and the assembly shown in Fig. 3, in normal direction with the surface of the ribbons and of the stratum of material to be 125 130

treated; said liquid is received by the funnel (9) and pipe (10). It must be observed, however, that the direction of the motion of the washing liquid may be disposed, though 5 always in the normal direction with respect to the surface of the assembly illustrated in Fig. 3, in a direction inverse to that aforementioned; in fact the liquid may arrive through pipe (10) and, after having traversed 10 the assembly shown in Fig. 3, it may be received in the interior of the cylinder (7) wherefrom it will be discharged through the exhaust hole (8). In the case illustrated, the 15 passage of the liquid through the material to be treated, is preferably effected by gravity, but it will be possible to predispose the several parts in such a manner that this passage takes place under pressure or suction. It is necessary that the washing liquid should 20 come against the surface of the ribbon so that the liquid will be compelled to effect a passage and be prevented from flowing away through other paths of less resistance; in the case and in the hypothesis illustrated, it is necessary 25 that the inlet of solvents in the cylinder (7) should be controlled so that the level of the liquid inside the cylinder does not surpass the chord of the arc of contact of the two ribbons on the barrel, and it is also necessary 30 that the assembly constituted by the two ribbons and by the material therein contained should strictly adhere to the surface of the cylinder barrel (7) and should not creep on it.

During the aforesaid operation, some holes 35 of the ribbon (1) which acts as filtering organ, are closed by particles of the material to be washed; further it must be noted that a sole passage does not always wash the material as much as desired, hence it will 40 often be necessary to submit the material to a second washing. For this purpose and also for the purpose of freeing the holes of the ribbon (1) which have become closed, as aforesaid, the assembly of the ribbons (1) 45 and (2) and of the material to be treated is subsequently traversed by a washing liquid or solvent in the direction opposite to that in which they had been traversed when they lay on the aforesaid cylinder (7). It will 50 be possible either to adopt the alternate disposition previously indicated, or to adopt a recoil and inverting roller (12) and to pass the inverted assembly under a second washing cylinder (11) constituted and working as 55 cylinder (7) in which the liquid has a motion in centrifugal direction by gravity. The same operation may take place more times (as shown in Fig. 1) by means of the recoil and inverting roller (12') and the washing 60 cylinders (13) and (14). The embodiments illustrated and indicated prevent the holes from being progressively closed as either of the two faces of the ribbon are alternately presented to the motion of the washing liquid.

65 In order to obtain the aforementioned ob-

jects it is necessary that the number of cylinders or generally the number of passages of the washing liquid through the material should be equal, in order that each ribbon be submitted to a washing operation after having 70 acted as filtering member.

We note that either by means of the type illustrated or of those based on the principles of the invention which, as aforesaid, must be considered included in the present application, it is possible by the successive enrichment of the solution to increase the concentration of the filtering liquid. In fact, it will be possible to pass the filtering liquid into the washing cylinder (14), to collect the 75 filtered liquid when flowing out through pipe (10'') and following the schematic indication of the arrow (17), to pass this liquid into the successive washing cylinder (13), to collect the filtering liquid when flowing 80 out through pipe (10') and to pass it, following the schematic indication of the arrow (17') into the successive washing cylinder (11) and so on.

After the assembly shown in Fig. 3 has 85 been sufficiently traversed by the washing liquid or solvent as aforesaid, the material must be separated from the transporting and retaining ribbons and it is necessary to recover, by suitable means, either the dried material or the washing liquid contained, absorbed or retained by the material or by the 90 ribbons. For obtaining the aforesaid separation, the assembly of the two ribbons and of the material therein contained, passes, 95 after leaving the last washing cylinder (14) over one or more recoil rollers (15) which in certain cases, may also be eliminated; the two ribbons (1) and (2) guided by the rollers (16) separate one from the other and 100 return to the positions (A) and (B) first considered. The material treated will leave the aforesaid ribbons and may be aided by the mechanical action of brushes (6) disposed against the inner surfaces of the ribbons, and 105 also by beaters, by drying devices, etc.

The material so separated will be collected in the tank (24) wherefrom it can be extracted for other uses; for instance it can pass to the devices which produce the separation of the treated material from the portion 110 of washing liquid which still remains in it, or which is retained by it.

Referring particularly to the embodiment shown in Fig. 5 (1) and (2) indicate the two 115 continuous ribbons, which following the direction of the arrow (30) reach the guide roller (4) and which pass through the two walls (31 and 32) and between two perforated plates (33 and 34) the holes or openings (35) of a plate corresponding exactly 120 with those of the other plate. Plate (33) constitutes the bottom of a tank (36) which the washing liquid passes following the direction of the arrow (37) through any suit-

able means; the plate (34) constitutes a wall of a closed tank (38) which bottom (39) presents an ample opening (40) closed by a spring diaphragm (41) fixed thereto in any 5 way, for instance by means of the ring (42) and of the bolt (43). Said spring diaphragm has its centre connected to a rod (44) to which very rapid alternations are imparted in the direction of the arrows (45) 10 and (46). The ribbons (1) and (2), after passing through the space between the two plates (33 and 34) passes through the vacuum between the two plates (47 and 48) which is long enough to avoid the dispersion 15 of the washing liquid in the direction of the arrow (30'); they pass around the roller (49) and go out for the further operations indicated in the main patent. The tank (36) also has an overflow (50) or the like through 20 which the treated liquid flows out in a small continuous stream; the entrance of the solvent is near the points (47) and (48) where the ribbons (1 and 2) leave the device; the overflow (50) corresponds to points (31 and 25 32) where the ribbons (1 and 2), containing the material to be treated, reach the device.

Referring particularly to Fig. 6 wherein like numbers of reference designate as much as possible, the corresponding parts of Fig. 30 5, we find, besides the other parts, a funnel (51) through which the solvent is poured, said funnel having at its bottom non-return 35 valve (52) by means of which its interior communicates with the interior of the chamber (32) which has an exhaust valve (52') submitted to the action of a suitable registering spring (not shown); this spring permits a limited opening of the valve only 40 when the pressure in chamber (38) has reached a given value. Beyond valve (52') there is an exhaust pipe (53) for the solvent which flows out in the direction of the arrow (54).

The device functions as follows: The 45 spring diaphragm (41) is rapidly vibrated by means of the rod (44) so that the solvent passes through the holes or openings (35) and traverses the two ribbons (1 and 2) and the material therein contained; with reference to Fig. 5, the solvent enters continuously in the direction of the arrow (57) and steadily flows away through the overflow 50 (50) after becoming enriched by passage through the device.

Referring to the embodiment shown in Fig. 6 each vibration of the spring diaphragm (41) causes the passage of a certain mass of solvent through valve (52) in the direction of the arrow (54) and the suction 55 of a portion of solvent contained in the tank (36) in the direction of the arrow (56). The action of the spring diaphragm (41) causes the passage to some solvent contained in chamber (38) in an opposite direction of the arrow (56) and also forces a part of the

solvent contained in the chamber (38) through the exhaust valve (52') and the pipe (53).

In such a way the vibrations of the diaphragm (41), besides producing the alternate passages of the solvent through the ribbons and the material therein contained, also produce a regular passage of the solvent from the funnel (51) to the exhaust pipe (53) in the direction of the arrow (54). 70 75

The two embodiments illustrated in Figs. 5 and 6 and the analogous ones which might be established on the basis of the principles indicated in the present application in view of the embodiment illustrated in the Figs. 1 80 to 4, have the following advantages:

They render possible to obtain a more compact and less bulky device.

The enrichment of the solutions reaches a greater value and consequently, in the successive operations, the device becomes more efficient, especially from the thermal point of view. 85

The number of vibrations of the spring diaphragm is controlled with respect to the speed of displacement of the ribbons in the direction of the arrow (30) between the two plates (33 and 34) so that the maximum useful efficiency is obtained, depending on the material to be washed and of solvent 90 employed. 95

The device disclosed in the present specification also set forth, the process of the successive enrichments of the solvent by placing several devices like those illustrated, one above the other, the exhaust solvent of one device being utilized for feeding the preceding device. 100 105

It must further be noticed that in order to withdraw the washed material from the ribbons (1 and 2), to recover from this material the solvent contained therein after the operation and to recover the washed material, dry and suitable for the further utilizations, it is possible to employ a warm gas working device in lieu of a solvent working device, but constructed in the same way as that illustrated in the drawings attached thereto. 110 115

We claim:

1. In an apparatus for washing with washing solvent raw material previously pulverized and granulated, in combination, an assembly comprising a continuous supporting porous ribbon, a second porous continuous ribbon adjacent to and above said supporting ribbon and channels in the adjacent surfaces of said ribbons forming a space containing the material to be washed, transporting means for said assembly and means for passing the washing solvent through said assembly alternately in a direction normal thereto. 120 125

2. In an apparatus for washing with washing solvent raw material previously pulverized and granulated, in combination, an as- 130

sembly comprising a continuous supporting ribbon, a second continuous ribbon adjacent to and above said supporting ribbon, said ribbons being flexible and porous so as to act 5 as a retaining means for the material and filtering means for the solvent, and channels in the adjacent surfaces of said ribbons forming a space containing the material to be washed, transporting means for said assembly and means for passing the washing solvent through said assembly in a direction normal thereto.

3. In an apparatus for washing with washing solvent raw material previously pulverized and granulated, in combination, an assembly comprising a continuous supporting ribbon, a second continuous ribbon adjacent to and above said supporting ribbon, said ribbons being flexible and porous so as to act 20 as a retaining means for the material and filtering means for the washing solvent, and channels in the adjacent surfaces of said ribbons forming a space containing the material to be washed, transporting means for 25 said assembly comprising rotating perforated cylinders containing the washing solvent and in frictional contact with said assembly, means for inverting said assembly with respect to each contact with the successive perforated cylinders comprising recoil and inverting rollers and means for collecting the 30 washing solvent after each passage through the assembly and for delivering the same to the interior of the succeeding perforated 35 cylinder.

4. In an apparatus for washing, with washing solvent, raw material previously pulverized and granulated, in combination, a plurality of hollow perforated cylinders containing 40 said washing solvent and disposed in vertical spaced relation, a hollow assembly comprising two channeled perforated flexible ribbons containing said raw material and a plurality of rollers frictionally engaging 45 said assembly, conducting said assembly adjacent said cylinders and inverting the same between successive contacts with said cylinders.

5. In an apparatus for washing, with washing solvent, raw material previously pulverized and granulated, in combination, a plurality of hollow perforated cylinders containing 50 said washing solvent and disposed in vertical spaced relation, a hollow flexible assembly comprising two channeled perforated ribbons containing said raw material, a plurality of rollers frictionally engaging said assembly, conducting the same in contact relation with said cylinders and inverting said 55 assembly after each contact, a plurality of funnels positioned below each hollow perforated cylinder and a plurality of pipes conducting said washing solvent after passage through said assembly into the next lower 60 hollow perforated cylinder.

6. In an apparatus for washing, with washing solvent, raw material previously pulverized and granulated, in combination, a plurality of hollow perforated cylinders containing 70 washing solvent and disposed in vertical spaced relation, a hollow flexible assembly comprising two channeled perforated ribbons containing said raw material, a plurality of rollers frictionally engaging said assembly, conducting the same in contact relation with said cylinders and inverting said assembly after each contact, a second plurality of rollers frictionally engaging said 75 ribbons to separate the same, scraping means engaging the channels in said perforated ribbons and a charging means positioned above said channels to fill the same with raw material to be washed.

In testimony whereof we affix our signatures.
